F. E. WELLMAN,
FUEL FEEDING SYSTEM,
APPLICATION FILED OCT. 7, 1916.

1,292,549.

Patented Jan. 28, 1919.

UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

FUEL-FEEDING SYSTEM.

1,292,549.

Specification of Letters Patent. Patented Jan. 28, 1919.

Application filed October 7, 1916. Serial No. 124,328.

To all whom it may concern:

Be it known that I, FRANK E. WELLMAN, a citizen of the United States, residing at Kansas City, county of Wyandotte, State of 5 Kansas, have invented certain new and useful Improvements in Fuel-Feeding Systems, of which the following is a specification, reference being had therein to the accompanying drawing.

10 My invention relates to furnaces using liquid or gaseous fuel and has for its object an apparatus for the control of the combustion in the said furnace at a safe distance therefrom.

15 I attain my object by devising means for controlling the supply of fuel and air separately, and at a safe distance from the furnace, as for example, 150 feet. This is accomplished by placing the pumps or 20 pressors for forcing the fuel and air into the combustion chamber in a control house at a safe distance from the furnace, and leading the fuel and air pipes from said control house to the furnace where the fuel is 25 mingled with the air and a combustible mixture is forced into the combustion chamber.

My invention is illustrated in the accompanying drawing, oil being taken as the fuel and air as the source of oxygen.

30 Figure 1 is a side view of the apparatus in conventional form.

Fig. 2 is a plan view of Fig. 1.

Referring to the drawings, A is an operating house. B is an oil pump. C is a 35 control valve. D is an oil pipe line constructed in the form of a U between the points d' and d'', leading from the pump B to the nozzle K, and containing the valve C. E is the oil supply pipe line. F is an air supply intake for the air compressor G. H is a control valve. I is an air pipe line between the compressor G and the nozzle K and containing the valve H. K is a mixing nozzle in which the oil and air are inti-

45 mately mixed, and from which this combustible mixture is expelled into the combustion chamber of the furnace. L is the combustion chamber.

50 The method of operation of this apparatus is as follows:

The pump B receives its supply of oil from pipe E and forces it in a continuous stream through pipe D and the control valve C. The supply of oil to the furnace is controlled by the hand operated valve C. In 55 order that oil may be supplied immediately to the furnace upon starting up, the pipe D is shaped somewhat in the form of a U so that the long section of the pipe between the points d' and d'' does not drain and 60 remains always full of oil. Thus the oil starts flowing into the furnace immediately upon opening the valve C. The compressor G receives the air from its intake pipe F and forces it through the pipe I fitted with control valve H for controlling the supply of air. The oil and air from the pipes D and I respectively come together in the mixing 65 nozzle K. Here the oil and air become intimately mixed, the oil being divided into a 70 fine mist. This combustible mixture then exhausts into the combustion chamber in the form of a spray, and readily burns.

Having thus described my invention, what I claim and desire to secure by Letters 75 Patent is:

In a system of the class described, a furnace, a control station situated at a safe distance from the furnace, fuel and air pipes leading from said control station to the furnace, a mixer thereat wherein the fuel and air are intimately intermingled, a valve in the fuel pipe at the control station, and means for maintaining the entire length of the fuel pipe between said valve and said 85 mixer filled with fuel at all times.

In testimony whereof I affix my signature.
FRANK E. WELLMAN.
